Primary Examiner—Louis S. Zarfas*Assistant Examiner*—Eric Watterson*Attorney, Agent, or Firm*—Myron B. Kapustij; Malcolm L. Sutherland[57] **CLAIM**

The ornamental design for a shower escutcheon, as shown and described.

DESCRIPTION

FIG. 1 is a front perspective view of a shower escutcheon showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a bottom plan view thereof; and,

FIG. 7 is a cross-sectional view taken along line 7—7 in FIG. 2.

The broken line showing of the handle in FIG. 1 is for purposes of illustration only and forms no part of the claimed design.
